UNITED STATES PATENT OFFICE.

JOSEPH S. BEEMAN, WILLIAM TAYLOR, AND FRANK KING, OF LONDON,
ENGLAND.

SECONDARY-BATTERY REGULATOR.

SPECIFICATION forming part of Letters Patent No. 291,465, dated January 1, 1884.

Application filed February 28, 1883. (No model.) Patented in England August 10, 1882, No. 3,813, and in France January 15, 1883, No. 140,860.

To all whom it may concern:

Be it known that we, JOSEPH SAMUEL BEEMAN, WILLIAM TAYLOR, and FRANK KING, all of 67 Strand, London, England, have invented 5
5 a new and useful Improvement on Secondary-Battery Regulators, (for which we have obtained patents in England, dated August 10, 1882, No. 3,813, and in France, dated January 15, 1883, No. 140,860,) of which the following is a specification.

Our invention relates to the regulating of secondary batteries, and has for its object to provide an efficient means for cutting the battery out of the charging-circuit before the 15 charging operation has been carried so far as to cause gas to be evolved from the battery-plates. To this end we combine in the battery-cell with the battery-plates proper a plate of relatively less storage capacity—which 20 may be called a "regulator-plate"—a gas-chamber, in which the gases evolved from said regulator-plate are received, and an elastic diaphragm, or its equivalent, which, by the pressure of the confined gases, is caused to 25 operate contact makers or breakers, at the same time retaining the gases in the cell. Inasmuch as gases will be evolved from the regulator-plate sooner than from the battery-plates proper, the charging-circuit will, under the arrangement just indicated, be broken before the latter plates begin to evolve 30 gases.

The annexed drawings will serve to illustrate various modes of performing our invention; but we would remark, as regards the contact-breaking or current-regulating apparatus, that the devices shown may be modified considerably without departing from the nature of the invention.

40 In all the figures like letters refer to like or corresponding parts.

Figures 1, 2, and 3 are respectively part plan, longitudinal section, and transverse section of a storage or secondary-battery cell. 45 Figs. 4, 5, 6, 7, and 8 represent various modifications of the diaphragm for operating the contact makers or breakers.

The cell is fitted with what we call a "gas-chamber," B, holding a plate, A, made of a size

proportional to the amount of energy intended 50 to be stored by the battery. The chamber B may be of any convenient size or shape. In the chamber B is formed a suitable orifice, C, fitted with an elastic or yielding diaphragm or equivalent, D, as shown in Figs. 2, 4, 5, 6, 55 and 7; or, in lieu of said diaphragm, a piston, D, as in Fig. 8, or apparatus similar to a Bourdon pressure-gage tube may be used. Said diaphragm or equivalent is acted on by the pressure of the gas evolved from the plate 60 A, contained in the chamber B, causing the said diaphragm or equivalent to be lifted and raise a lever or other device, G, which rests or is fixed on it, and said lever or device is made to operate any well-known electrical 65 contact-breaking apparatus, or such apparatus as are shown in Figs. 1 and 3, where G is the lever or equivalent, actuated by the diaphragm D, or its equivalent—such as the sliding or telescopic tube arrangement in Fig. 70 4, or the bellows arrangement in Figs. 5 or 6—said lever G being furnished at one end with a rod, H, dipping into a cup, I, supplied with mercury or other metallic contact, said mercury or equivalent being in electrical 75 connection with the electric generator or any contact-breaking apparatus; or, instead of employing a lever to break contact when the diaphragm rises, the yielding diaphragm may contain mercury, as shown in Fig. 7, which, 80 when elevated, makes contact with the conductors K, so as to cause the current from the charging-circuit to be cut out or diverted.

In employing an apparatus for regulating secondary batteries, we proportion the size of 85 the plate A, by making such plate smaller than the plates or electrodes of the battery proper, according to the amount of energy to be stored in the battery. We find that the plate A being made, say, nine-tenths of the storage capacity 90 of any other plate in the battery, gives a desirable result, and that the battery is thereby cut out of the charging-circuit some time before the gas would otherwise be evolved from the battery-plates, thus prolonging considerably the life of the plates composing the 95 battery.

We are aware that valves have been ap-

plied to batteries to permit the escape of gas; but according to our invention we retain the gas evolved from the plate A, and allow it to operate a diaphragm or equivalent, for the purpose described.

We claim as our invention—

The combination, in a secondary-battery cell, with the battery-plates proper, of a regulator-plate, A, of relatively less storage capacity, to a gas-chamber, B, and the elastic diaphragm D, or its equivalent, for operating contact

makers or breakers, substantially as and for the purposes hereinbefore set forth.

In testimony whereof we have signed this specification in the presence of two subscr- 15
ing witnesses.

J. S. BEEMAN.

W. TAYLOR.

FRANK KING.
